UNITED STATES PATENT OFFICE.

JOHN J. SHEEHAN, OF ROANOKE, VIRGINIA.

PNEUMATIC HAMMER.

1,126,890.

Specification of Letters Patent.

Patented Feb. 2, 1915.

Application filed August 26, 1914. Serial No. 559,610.

To all whom it may concern:

Be it known that I, JOHN J. SHEEHAN, a citizen of the United States, residing at Roanoke, in the county of Roanoke and State of Virginia, have invented certain new and useful Improvements in Pneumatic Hammers, of which the following is a specification.

This invention relates to pneumatic hammers or riveters and has for its object to provide means for retaining the tool to the barrel of the hammer when the hammer is held with its outer end downward or when the air is accidentally admitted to the hammer piston at a time when the tool is not in position against the work. As is well known to those acquainted with the art, these hammers are made with the tool unsecured to the hammer barrel and consequently an ill-timed opening of the air valve is very likely to shoot the tool through the air instead of driving it against the work. It will be readily seen that serious accidents may readily result from this, and the present invention is therefore intended to provide simple means for preventing this dropping or discharge of the tool and at the same time to allow the ready removal and exchange of tools as is necessary in the routine of work.

In the drawings, Figure 1 is a part side elevational view and part sectional elevational view of a pneumatic hammer having my invention applied thereto. Fig. 2 is a broken perspective view of the sleeve of my invention and Fig. 3 is a similar view of an alternative arrangement of sleeve.

Referring now to these drawings, in which like parts are similarly designated wherever they occur, 1 represents an air hammer having a barrel 2 and piston 3. The tool 4, in the present instance being a rivet set, is provided with a shank 5, collar 6, body portion 7 and working face 8. It is the customary practice to simply enter the shank 5 of the tool into the bore 9 of the barrel, holding the tool there with the hand until the working face 8 is in position against the work. When against the work the tool will be held in the bore or cavity 9 without the aid of the operator and without a retaining device. The blow on the tool is obtained by admitting compressed air behind the piston 3 which piston is consequently driven downward, striking the shank of the tool. The trigger 10 is ordi-

narily provided for shutting on and off this supply of compressed air. It will be seen that if the air is turned on with the tool unsecured in the cavity 9 the tool will be thrown or shot out of the hammer as before described. Various means have been heretofore provided for retaining this tool, but none so far as I am aware have ever been entirely successful. They are too difficult to detach for changing the tool or they are not sturdy enough to stand up under the severe punishment they receive. Others also have proved to be unreliable and serve merely to hold the tool in place when the air is not turned on. The standard hammer is customarily provided with a circumferential groove 11 about the outer end of the barrel to accommodate a retainer of this latter type and the embodiment of the features of my invention on a hammer makes it unnecessary to abandon this groove which is now found in most hammers. In addition to retaining this feature, my device is a simple, durable, effective and easily detachable one, the elements and operation of which I will now proceed to describe.

Rigidly secured to the hammer barrel near its outer end and projecting laterally from the outer surface thereof are short studs or dowels 12. Encompassing the outer end of this hammer barrel 2 and embracing the said studs 12 I provide a hollow sleeve 13, this sleeve being shown with a slightly reduced portion at its outer end 14 and having an inwardly extending collar 15 at its extreme outer end. The bore of this hollow sleeve is made at the said collar 15 of sufficient diameter to accommodate the body 7 of the tool 4 and at the reduced portion 14 the bore is made suitable for receiving a coil spring 16. The bore of the inner end of the sleeve 13 is, of course, made suitable to fit over the outer end of the hammer barrel, and this bore as well as the bore of the portion at 14 is made slightly greater than the diameter of the collar 6 on the tool 4.

When the tool 4 is in position in the hammer the inner face of the collar 6 is against the outer end 17 of the hammer barrel and is held thereagainst by the compression of the spring 16 which is compressed between the outer face of the collar 6 of the tool and the inner face of the collar 15 of the hollow sleeve.

The internal surface of the hollow sleeve

13 is provided with grooves which are adapted to accommodate the studs 12. These grooves consist of longitudinally disposed entering grooves 18 (see Fig. 2), a continuous circumferential turning groove 19 and longitudinally extending retaining grooves 20. The entering grooves 18 extend from the barrel end of the sleeve to the turning groove 19 and the retaining grooves 20 extend back a short distance from the turning groove toward the barrel end of the sleeve and at a slightly different circumferential position on the internal surface of the sleeve than the entering grooves.

15 An entering and a retaining groove is supplied for each stud or dowel 12 and they are so disposed on the inner periphery of the hollow sleeve that when the sleeve is applied to the barrel of the hammer the 20 grooves will register with the said studs.

The various parts are so proportioned that when the studs 12 are in position in the bottom of the retaining grooves 20 the spring 16 will be compressed between the 25 collars aforesaid.

25 The manipulation of the device in applying a tool is as follows: The shank 5 of the tool 4 is inserted into the cavity 9 of the hammer barrel and the spring 16 is put in position over the body portion of the tool. The hollow sleeve 13 is then slipped over these parts and over the outer end of the hammer barrel, the sleeve being turned so that the studs 12 will enter the grooves 18.

30 In order to push the hollow sleeve far enough over the hammer barrel to bring the studs 12 into registry with the circumferential turning groove 19 the spring 16 must be compressed between the collars on the 35 sleeve and on the tool. The hollow sleeve is then revolved, the studs turning in the turning groove until they register with the retaining grooves 20 when the compression of the spring will seat them in the bottom 40 of these retaining grooves. The compression of the spring 16 should be enough that when the studs 12 are so seated in the bottom of the retaining grooves the spring will still be slightly compressed. With the parts 45 so applied the tool 4 will be firmly secured to the hammer barrel and cannot be removed without a reversal of the operation just described for its application.

In addition to holding the studs in the 55 bottom of the retaining grooves the spring 16 serves also to cushion the blow of the tool against the collar 15 when the tool is not against the work and the hammer is operated. Likewise, the blows of the tool 60 against this spring will force the sleeve all the harder against the studs so that at this time the element of safety is the greatest.

In Fig. 3 I have shown a slightly altered arrangement of the entering and retaining 65 grooves, their functions being identical with

those of the grooves in Fig. 2. For ease of manufacture, however, the arrangement in Fig. 2 is preferable, as the circumferential groove may be turned out in a lathe, the entering grooves slotted out, and the retaining 70 grooves may be formed by simply drilling holes at the desired locations, removing the metal all the way through the sleeve instead of just on the internal surface.

In some previous devices also it has been 75 difficult to make the parts of a size suitable for receiving the larger tools. In my device I am enabled to use any tool on which the collar 6 is not larger than the end of the hammer barrel and in the drawings I have 80 shown this hammer barrel as enlarged near its outer end to accommodate an even larger tool. Hammers ordinarily do not have this enlargement and for smaller tools it is not needed. Its use, however, as stated, allows 85 the application of the larger sized tools.

It will thus be seen that I have provided an improvement in this art that will accomplish the objects desired.

It will be evident that those skilled in the 90 art may make various changes in the details of this device within the scope of the claims without departing from the spirit thereof.

Having thus described my invention what I claim is:

1. In a pneumatic hammer a hollow tool-retaining sleeve adapted to embrace the outer end of the barrel of the said hammer, in combination with laterally projecting studs affixed to the barrel of said hammer 100 near the outer end thereof, said hollow sleeve being provided on its internal surface with entering and retaining grooves adapted to register with and accommodate the 105 said studs.

2. In a pneumatic hammer a hollow tool-retaining sleeve adapted to embrace the outer end of the barrel of the said hammer, in combination with laterally projecting studs affixed to the barrel of said hammer 110 near the outer end thereof, said hollow sleeve being provided on its internal surface with longitudinally disposed entering grooves, a circumferentially disposed turning groove, and longitudinally extending retaining 115 grooves, said entering, turning and retaining grooves being adapted to accommodate the said studs.

3. In a pneumatic hammer a hollow tool-retaining sleeve adapted to embrace the 120 outer end of the barrel of the said hammer, in combination with laterally projecting studs affixed to the barrel of said hammer near the outer end thereof, said hollow sleeve being provided on its internal surface 125 with entering and retaining grooves adapted to register with and accommodate the said studs, and being further provided at its outer end with an internally disposed collar, a tool having a collar mounted on 130

end and having the body therecif of less diameter than the internal diameter of said hollow sleeve, the bore of the said internally disposed collar being such as to accommodate the body of said tool, and a spring interposed between the collar on said tool and the collar on said sleeve and adapted to occupy the annular space between the body of said tool and the internal 10 surface of said sleeve.

4. A pneumatic hammer having laterally projecting studs affixed to the barrel thereof near its outer end, in combination with a hollow tool-retaining sleeve adapted to embrace the outer end of the said hammer, said hollow sleeve being provided with reversely and substantially longitudinally disposed entering and retaining grooves adapted to accommodate the said studs, a tool disposed 20 for its major portion within said hollow sleeve, and a spring surrounding said tool and adapted to hold the same against the end of the barrel of the hammer, the reaction of the other end of said spring serving 25 to hold said studs within the said retaining grooves.

5. In a pneumatic hammer, a barrel and a tool in combination with a tool retaining sleeve and a coil spring, said barrel being 30 provided at its outer end with a cavity to receive the said tool and being provided near its outer end with laterally projecting studs, said tool having a shank at its inner

end adapted to enter the cavity in the end of said barrel and being provided with a collar 35 adjacent the said shank, the outer portion or body of said tool being of less diameter than the said collar, said tool retaining sleeve being hollow and being adapted at its inner end to embrace the outer end of 40 said barrel, the internal surface of said sleeve being provided with entering and retaining grooves adapted to engage the said studs on the said barrel, said retaining sleeve being provided at its outer end with 45 an inwardly disposed collar, the opening through the said collar being of less diameter than the opening through the remainder of the said hollow sleeve and of such a size as to accommodate the body portion 50 of the said tool, the said coil spring being disposed externally of the body portion of said tool and internally of the said hollow sleeve and longitudinally between the collars on the said tool and said sleeve, said 55 spring being thereby adapted to hold the said tool against the said barrel and the said studs within the said retaining grooves of said sleeve.

In testimony whereof I affix my signature 60 in presence of two witnesses.

J. J. SHEEHAN.
